UNITED STATES PATENT OFFICE.

WILLIAM H. BURNHAM AND JOHN H. MILLER, OF BATAVIA, ILLINOIS, AS-SIGNORS TO THE UNITED STATES WIND ENGINE AND PUMP COMPANY, OF SAME PLACE.

WINDMILL.

SPECIFICATION forming part of Letters Patent No. 391,401, dated October 23, 1883.

Application filed November 14, 1887. Serial No. 255,038. (Model.)

To all whom it may concern:

Be it known that we, WILLIAM H. BURNHAM and JOHN H. MILLER, citizens of the United States, and residents of Batavia, in the county of Kane and State of Illinois, have invented new and useful Improvements in Windmills, of which the following is a specification, reference being had to the accompanying drawings illustrating the invention, in which—

Figure 1, Sheet 1, is a perspective representation of a windmill in which is embodied our invention; Fig. 2, Sheet 2, an enlarged elevation of the truss-frame, turn-table, and other mechanism connected therewith; Fig. 3, an elevation, enlarged, of a detail portion; Fig. 4, Sheet 1, an inverted and enlarged perspective representation of one of the angle-irons by which the fan-bars are secured to the radial arms of the wind-wheel; Fig. 5, Sheet 3, a plan or top view of Fig. 1.

This invention relates to novel means for regulating the speed of the wind-wheel, and to angle-irons for securing the fan-bars to the arms of the wind-wheel, as hereinafter fully set forth and shown.

G represents the tower, V the tail-vane, T the side vane, S A F f the wind-wheel, and h the turn-table, of an ordinary windmill, except the angle-irons Y, which constitute a portion of our invention.

B represents the truss-frame, which is constructed higher and stronger than has been the custom, and with cross-timbers 4 and 5 for the support of the auxiliary mechanism employed. The tail-spar J engages a strong socket-plate, X, which is pivoted to the turn-table and othersupporting parts in a substantial manner, by means of which the said vane may have the ordinary swinging movement.

The fan-bars f f, &c., are connected with the radial arms of the wind-wheel by means of angle-irons Y. (More clearly shown at Fig. 4.) These irons consist of a main cap-plate which has cast solid with it two angular standards supporting two seats, b. These seats are provided at their side edges with flanges ee, so that when the seats are bolted to the arms of the

wheel there will be no lateral movement of the iron. Between the standards which support the seats b are formed sockets d d, in which the ends of the fan-bars f are made to fit, and projecting up from the main plate of the angle-irons are pins c c, which, respectively, enter said bars, so that when the angle-iron is bolted to an arm, A, the fan-bars will be firmly held in place without any other fastening.

The means for regulating the speed of the wind-wheel is: Pivoted at I on the turn-table h is a weighted lever, K W, which holds the tail-spar J substantially in line with the shaft of the wind-wheel up to a certain pressure of wind on the wheel. After such certain pressure has been attained the wheel would turn edgewise too much to the wind were it not for the auxiliary weighted lever N L, which is pivoted to a central support at P, and has a connection with the lever K by means of a rod, M. Above the weight W, and on rod M, is an adjustable stop, 3, and on the lower end of the rod is a nut or knob, and on the lever K is affixed an eyebolt, j, through which that portion of the rod M below the stop 3 passes. This construction is such that by adjusting the stop 3 on rod M the lever K W may have any desired movement before the auxiliary lever N L has any effect in resisting the pressure of the wind on the wheel; but at such times as the upper lever is brought into use by the rod M and its stops such an additional force will so resist the action of the wind on the wheel as to keep it in position to rotate after the lever K W has lost its power for that purpose.

a a represent the irons for securing the turn-table to the lower track, and R represents the rollers between the turn-table and track.

7 r represent the positions a buffer and buffer-stop may occupy to prevent the tail-vane from a too sudden stop in changing its position.

H 2 is the post through which a furling cord or rod, O, passes. By drawing on this cord both levers K W and N L are elevated and the wheel put edgewise to the wind.

C E represent the principal rods for the support of the vanes with the top of the tower

D g, and U is the rod which serves to connect the elbow portion of the lever K W with the plate which supports the tail-vane.

Having thus described our invention, what we claim as new is—

- 5 1. An improvement in windmills, consisting of the lever K, weighted at W, linked to the tail-vane, and pivoted to the turn-table h at I, in combination with an upper lever, N, 10 which is weighted at L and pivoted to the top P of the central support, H 2, and a connecting-rod, M, which is jointed to the lever N, passes through the eyebolt j, and is provided with an adjustable stop, 3, and an enlarged 15 lower end, the tail-vane J, turn-table h, and wind-wheel, as specified.

2. The angle-iron Y cast in one piece of metal, with a base-plate supporting two standards, which are provided with flanged seats e b e b, and the pins c e, projecting into the recesses d d between the standards and from the main plate, in combination with the fan-bars f, held in said recesses, and the arm of the wheel secured to the seats b b, substantially as specified and shown. 20
